LUBRICATING DEVICE FOR CUT-OFF KNIVES

Bernard Wellnitz, Alton, Ill., assignor to Owens-Illinois Glass Company, a corporation of Ohio

Application June 14, 1937, Serial No. 148,090

17 Claims. (Cl. 49—5)

The present invention relates to an apparatus for lubricating the cut-off knives of rotary bottle forming machines of the Owens type shown, for example, in U. S. Letters Patent No. 1,185,687, dated June 6, 1936.

In machines of the type set forth above, it is essential that the cut-off knives, which travel with the molds and which rock across the bottom of the blank molds as the latter lift from the molten glass to sever the strings of glass which depend from the lower ends of the blanks when the same are gathered into the blank molds, be lubricated periodically in order that they may operate efficiently. Failure to lubricate the cut-off knives adequately results in an undue amount of friction between the knives and the bottom of the blank molds which in turn presents a great number of undesirable characteristics in the finished product as well as presenting numerous operating inefficiencies.

Among the undesirable characteristics presented in the finished product by failure to lubricate the cut-off knives, are the occurrence of filings, both from the cut-off knives and from the bottom of the blank molds, which fall into the supply pool of molten glass. In addition, rough cut-off scars appear on the finished articles due in a measure to the attendant deterioration of the ordinarily sharp knife edges. Furthermore, because of the fact that the knives, when dull, fail to properly sever the tails or strings of glass from the charges in the blank molds, small particles of glass adhere to the knives and frequently spill over the edge of the furnace forehearth and find their way into the articles contained in the finishing molds beneath the blank molds.

Among the operating inefficiencies presented by failure to adequately lubricate the cut-off knives, wear of the blank molds and the consequent necessity for frequent replacement thereof is the most serious. In addition, inability of the knives to remain sharp and give satisfactory service is a penalty for failure to lubricate the knives. Furthermore, direct damage to the nose of the blank mold by the cutting or scraping action of a dull knife is likely to occur should the knives remain not lubricated for a period of time.

Heretofore greasing or lubrication of the cut-off knives in machines of the type referred to has been accomplished manually by means of a swab in the hands of the operator of the machine. The time interval between successive greasing operations varies greatly, the operator applying lubricant to the knives whenever it occurs to him

to do so, or when the character of the tails or strings issuing from the cut-off knives is such that the matter is brought to his attention. No system of uniform lubrication of the cut-off knives has been successfully developed and consequently a considerable portion of the time of an operator that might well be devoted to other pressing matters is consumed in performing the relatively difficult, energy-consuming and time-consuming operation of applying lubricant to the moving cut-off knives.

The principal object of the present invention is to provide a uniform system of lubrication for the cut-off knives in forming machines of the Owens type, and toward this end the invention contemplates the provision of a fully automatic lubricating apparatus which will relieve the operators of such machines of the responsibility of attending to the matter of knife lubrication.

The provision of such an apparatus which is capable of quick attachment to the machine which it is designed to serve and, more important, one which is also capable of quick detachment therefrom in case of an emergency, and one which will effectively apply a uniform amount of lubricant to each and every cut-off knife once during each revolution of the machine, are further desiderata that have been borne in mind in the production and development of the present invention.

In the accompanying drawings:

Fig. 1 is a top plan view of the lubricating apparatus, showing the same applied to a forming machine of the Owens type.

Fig. 2 is an elevational view of the apparatus with certain parts thereof shown in section and other parts thereof broken away to more clearly reveal the nature of the invention.

Fig. 3 is an enlarged fragmentary sectional view taken vertically and longitudinally through an attachment arm forming a part of the lubricating apparatus.

Fig. 4 is a sectional view taken substantially along the line 4—4 of Fig. 3.

Fig. 5 is a side elevational view of the apparatus, showing the same applied to the forming machine.

Fig. 6 is a sectional view taken substantially along the line 6—6 of Fig. 5.

Fig. 7 is an end elevational view of the apparatus shown in Fig. 5.

Fig. 8 is an enlarged end elevational view of the apparatus, certain parts being broken away and others being shown in section to more clearly reveal the nature of the invention.

Fig. 9 is a sectional view taken substantially along the line 9—9 of Fig. 8.

Fig. 10 is a sectional view taken substantially along the line 10—10 of Fig. 8.

5 Fig. 11 is a fragmentary side elevational view of the disclosure of Fig. 10.

Fig. 12 is a sectional view taken substantially along the line 12—12 of Fig. 8, and

10 Fig. 13 is a sectional view taken substantially along the line 13—13 of Fig. 8.

Referring now to Fig. 5, the lubricating apparatus is mounted on a stationary platform 20 which is supported from the floor or foundation of the forming machine 21. The platform 20 15 occupies a position adjacent the forming machine 21 close to the furnace (not shown) and on the approach side thereof.

The apparatus includes a supporting column 22 mounted on the free end of a link 23 which is 20 hinged to a second link 24 which is in turn hinged to a bracket 25 (see also Fig. 7) mounted on the platform 20. The upper end of the column 22 has mounted thereon a tubular supporting arm 26 which serves to support a major portion of the 25 operative lubricating instrumentalities and the inner end of which is releasably attached (in a manner presently to be described) to an attachment block 27 (Figs. 1 to 4 incl. and 7) which is secured to the forming machine base 28 (Fig. 5).

30 By virtue of the releasable attachment between the tubular supporting arm 26 and the attachment block 27, and the folding link construction 23, 24, which serves to support the column 22, the entire lubricating apparatus is movable 35 toward and away from the forming machine and may assume the inoperative dotted line position indicated in Fig. 5. A coil spring 29 connected to the links 23 and 24 normally urges these 40 two members into folded position when the apparatus is not attached to the attachment block 27.

Referring now to Figs. 3 and 4, the attachment means whereby the inner end of the supporting arm 26 may be releasably secured to the attachment block 27 consists of a squared flange 30 45 adapted to abut against the outer face of the attachment block 27 and through which a pair of attachment pins 31 secured in the block 27 are adapted to extend. A sleeve 32 surrounds 50 the supporting arm 26 and has a pair of attachment lugs 33 which overlie the square flange and are adapted to extend into recesses 34 formed in the sides of the pins 31 and maintain the flange 30 in engagement with the face of the 55 attachment block 27. Coil springs 35 which are disposed between brackets 36 secured to the flange 30 and respective lugs 37 formed on the sleeve 32 serve to apply a torque to the sleeve 32 in a clockwise direction, as viewed in Fig. 4, to urge 60 the lugs 33 into engagement with their respective attachment pins 31 and maintain the apparatus in operative engagement with the forming machine 21.

The tubular supporting arm 26 is secured to the 65 upper end of the column 22 by means of bolts 40 which extend through a face plate 41 formed on the column and are threadedly received in a pair of lugs 42 that project through slots 43 provided in the sleeve 32. A lever 44 70 (see also Fig. 5) formed on the sleeve 32 extends upwardly therefrom and is accessible to the operator of the machine. Swinging movement of the lever 44 in a counter-clockwise direction, as viewed in Fig. 3, will serve to diseng- 75 gage the attachment lugs 33 from their respec-

tive attachment pins 31 and permit the entire apparatus to be moved automatically to the dotted line position of Fig. 5 with the links 23, 24, in their folded or collapsed position.

The outer end of the tubular supporting arm 5 26 serves to support thereon a three-way fitting 45 (Fig. 8) which carries at its upper end a vertically extending sleeve 46 provided with a slot 47 in the side thereof adjacent its top. A pair of lugs 48 (see also Fig. 2) formed on the sleeve 10 46 on opposite sides of the slot 45 serve to rotatably support therebetween a shaft 49 on which there is mounted a gear 50 which meshes with a series of perforations 51 provided in an inner sleeve 52 which is disposed within the sleeve 46. 15 A hand wheel 53 formed on the shaft 49 operates upon turning movement thereof in one direction or the other to raise or lower the inner sleeve through the medium of the gear 50 and perforations 51. A collar 54 mounted on the upper end of the outer sleeve 46 is provided with a boss 55 through which there extends a locking bolt 56 having a handle 57 associated therewith. The locking bolt 56 serves to bind the inner sleeve 52 within the outer sleeve 46 in any desired 20 adjusted vertical position.

A central shaft 58 extends through the sleeve 52, is rotatable therein, and is capable of limited vertical sliding movement therein. The shaft 58 carries adjacent its upper end a head 60 (Figs. 30 8 and 12) which is provided with pairs of oppositely extending lugs 61. A pair of oppositely extending radial swab-carrying arms 62 (see also Fig. 1) have their inner ends hingedly connected by means of pintles 63 to the lugs 61. The free 35 ends of the arms 62 have mounted thereon knife lubricating devices or swabs 64 which are in the form of lubricant absorbing pads and which are adapted to make successive contact with the upper surfaces of the cut-off knives of the forming machine to apply lubricant thereto. The shaft 58 is adapted to be periodically indexed or turned through an angle of one hundred and eighty degrees, in a manner that will subsequently be described to cause the swabs 64 to successively register with successive cut-off knives. 45 In Fig. 1, one of the cut-off knives K is shown in its extended position swung outwardly from the bottom of the blank mold M with one of the swabs 64 in contact therewith during actual lubrication 50 thereof.

The swabs 64 carried at the free ends of the arms 62 are normally supported in their circular path of movement slightly above the level of the extended cut-off knives K. Upon periodic indexing of the shaft 58, the swabs 64 are adapted to be moved over the extended cut-off knives successively and be lowered into engagement therewith in passing. Accordingly, each arm 62 is provided with a depending stub shaft 65 (Figs. 2 and 8) carrying rollers 66 at its lower end. A cam member 67 having a cam surface 72 which is substantially circular in form is carried at the upper end of the sleeve 52 and the rollers 66 are adapted to bear against the cam surface 72 under the influence of gravity as exerted by the outwardly extending radial arms 62 and under the influence of a pair of coil springs 68 connected to trunnions 69 carried by the stub shafts 65 which tend to draw the stub shafts 65 inwardly 65 and maintain the rollers 66 in constant engagement with the cam surface 72. The cam surface 72 is provided with a flattened area 76 (Figs. 1 and 12) which is oriented directly toward the knife K at its precise moment of contact with 75

one of the swabs 64. The rollers 65 are adapted to travel inwardly on the flattened area 70 to permit the arms 62 to dip momentarily and cause the swabs 64 to descend upon the respective knives K which they are about to lubricate. Depressions 71 formed in the cam surface 72 provide a dwell position for the arms 62 and swabs 64 carried thereby between successive indexing operations of the shaft 58.

In order to protect the operator of the forming machine against accidental contact with the moving arms 62 and swabs 64, a guard or cage is designed to enclose these moving parts throughout a portion of their path of movement. The guard (Figs. 1 and 8) consists of upper and lower radially extending straps 74 and 75 respectively which are connected at their outer ends to an accurate strap 76. The inner ends of the straps 74 are connected to a ring member 77 surrounding the shaft 58 while the inner ends of the straps 75 are secured to the cam member 67.

Referring now to Figs. 8 and 13 wherein the mechanism for periodically indexing the shaft 58 is disclosed, the lower end of the inner sleeve 52 serves to support a casting 80 by means of an integrally formed split collar connection 81. The casting 80 is provided with a chamber 82 therein which is closed by means of a cover plate 83. The shaft 58 extends downwardly through the casting 80 and chamber 82 and has secured thereto above the casting 80 one element 85 of a ratchet type clutch. The other element of the clutch, which is a counterpart of the element 85, is in the form of a collar 86 loosely mounted on the shaft 58. The collar 86 is provided with a gear 87 integrally formed thereon which is in constant mesh with a sliding rack bar 88 (see also Figs. 5 and 6) designed for reciprocation in the casting 80. A coil spring 89 disposed between the collar 86 and the lower end of the inner sleeve 52 serves to normally urge the two elements of the clutch 85, 86 into engagement. The collar 86 is provided with a flange 84 thereon and a finger 78 formed on a sliding clutch bar 79 mounted for vertical sliding movement in the casting 80 extends beneath the flange 84 for the purpose of lifting the collar 86 to disengage the clutch. The clutch bar 79 is actuated manually by means of a lever 73 (Fig. 11) pivoted to a bracket 59 formed on the casting and connected by a link 38 to the clutch bar 79. A spring detent mechanism 39 or catch serves to hold the clutch bar 79 in its elevated position to disengage the two elements of the clutch 85, 86.

The rack bar 88 is normally maintained in its retracted position by means of a coil spring 90 which bears at opposite ends thereof against a collar 91 and against a portion of the casting 80. The rack bar 88 is adapted to be periodically moved to its advanced or extended position by means of a pusher rod 92 which is in alignment therewith and which is supported in bearings 93 carried by the attachment block 27. The inner end of the pusher rod 92 is connected by means of a pin and slot connection 94 (Figs. 5 and 6) to an eccentric point on a disk 95 which is mounted upon a shaft 96 journaled in the base 28 of the forming machine. The shaft 96 has mounted thereon a gear 97 which meshes with the driving gear 98 of the forming machine 21.

From the above description of parts, it will be seen that when the apparatus is in operative position with respect to the forming machine 21, the gear 97 and disk 95 are continuously rotated, thus imparting reciprocal motion through the pin and

slot connection 94 to the pusher rod 92. Reciprocal motion is imparted to the rack bar 88 by means of the pusher rod 92 which periodically causes the bar to be advanced and by means of the coil spring 90 which serves to retract the rack bar 88 each time the pusher rod 92 is withdrawn. Reciprocation of the rack bar 88 causes the gear 87 which is in constant mesh therewith to be rotated alternately in opposite directions, thus periodically indexing the shaft 58 by causing it to be turned through an angle of one hundred and eighty degrees. Each movement of the shaft 58 causes the radial swab-carrying arms 62 to be rotated from one position of dwell throughout one hundred and eighty degrees to the other position of dwell as determined by the depressions 71 (Fig. 12) provided in the cam 67.

The movement of the arms 62 between each position of dwell is such that one of the swabs 64 passes and lubricates one of the cut-off knives K as previously described while the other swab 64 passes, contacts, and receives lubricant from a lubricant feeder 100 (Figs. 1, 2, 8 and 9). The lubricant feeder 100 is in the form of a hollow spool which is mounted upon a hollow stem 101 supported at the outer end of a bracket 102 which is mounted on one of the lower guard straps 75. Lubricant is fed to the interior of the feeder 100 by way of a flexible conduit 103 and passes outwardly through the spool-like feeder through apertures 104 provided therein. The feeder 100 is positioned in the path of movement of the swabs 64 and the upper surface thereof extends slightly above the plane of movement of the swabs. Thus, in passing from one position of dwell to the other, the swabs come into contact with the feeder 100 and receive lubricant therefrom.

In order to maintain a uniform supply of lubricant in the lubricant feeder 100, the lower end of the flexible conduit 103 communicates with the interior of a lubricant reservoir 99 through the stem 105 of a stationary piston 106. The piston 106 and stem 105 are held stationary by means of an outwardly extending supporting arm 107 formed on the collar 54 and by means of which the stem 105 is supported. The lubricant reservoir 99 is in the form of an open-ended cylinder in which the piston 106 is disposed. Means is provided for gradually moving the cylinder 99 upwardly with respect to the piston 106 in order to force lubricant through the piston 106, stem 105 and conduit 103 to the lubricant feeder 100. Accordingly, the cylinder 99 is mounted on the upper end of a vertically extending shaft 108 which is supported for rotation in the casting 80. The medial region of the shaft 108 is threaded and is designed for threaded engagement with internal threads provided in a split collar 109 (Figs. 10 and 11). The sections 60 of the split collar 109 are carried by arms 110 which are mounted for swinging movement about the vertical axis of a bolt 111 which extends into the casting 80. A finger 112 formed on each section of the split collar 109 extends into a groove 113 formed in a short rock-shaft 114 which is supported in bearings 115 formed on the casting 80. The grooves 113 are inclined with respect to each other in such a manner that rocking movement of the shaft 114 in one direction 70 or the other will cause the split collar 109 to open or close, as the case may be, as the fingers 112 follow the paths provided by the grooves 113. A handle 116 formed on the rock-shaft 114 facilitates turning thereof. From the above descrip- 75

tion, it will be seen that upon opening of the split collar 109, the threaded portion of the shaft 108 is released and the lubricant cylinder 99 may be lowered for the purpose of refilling the same.

5 Means is provided for periodically turning the shaft 108 at selected rates of speed to cause the lubricant cylinder 99 to be fed upwardly with respect to the piston 106 in order that lubricant may be fed to the feeder 100 as required. Toward this 10 end, the lower portion of the shaft 108 has splined thereto a gear 120 (Figs. 8 and 13) which is in constant mesh with a plurality of gears 121, 122 and 123 which are mounted upon and secured to the lower ends of respective shafts 124, 125 and 126 which are rotatably journaled in a substantially triangular plate 127. The plate 127 is pivoted for swinging movement about the axis of the shaft 108. The upper ends of the shafts 124, 125 and 126 have secured thereto respective gears 128, 129 and 130 of decreasingly smaller size and of varying elevations. These latter gears are adapted upon angular adjustment of the plate about the axis of the shaft 108 to selectively be placed in mesh with respective gears 131, 132 and 133 which are mounted on the shaft 84 adjacent the lower end thereof. The gears 131, 132 and 133 are of increasingly larger size and thus it will be seen that intermittent rotary motion of the shaft 84 may selectively be transmitted to the 20 shaft 108 at selected speed ratios from any one of the three gears 131, 132 or 133 through the respective gears 128, 129 or 130 which are designed for contact therewith and through one of the gears 121, 122 or 123 as the case may be to 30 the gear 120. In order to effect angular adjustment of the triangular plate 127 to vary the speed ratio between the shafts 84 and 108, the plate 127 has formed thereon an arm 135 which carries at its outer end a spring pressed pin 136 designed 40 to be selectively received in any one of a plurality of holes 137, 138 or 139 provided in a flange 140 formed on the casting 80.

In the operation of the lubricating apparatus, the lubricant reservoir or cylinder 99 (Fig. 8) is initially filled with a lubricant suitable for application to the cut-off knives K (Fig. 1) of the forming machine 21. This operation is performed by turning the handle 116 (Figs. 8, 10 and 11) in such a manner that the fingers 112, in following the inclination of the grooves 113 formed in the shaft 114, are spread apart, thus opening the split collar 109 and releasing the threaded portion of the shaft 108. The reservoir 99 may then be lowered to clear the piston 106 in order that 50 lubricant may be placed in the interior thereof. The filled reservoir is reapplied to the piston 106 and the split collar 109 is closed over the threaded portion of the shaft 108.

After the reservoir 99 has been filled, the entire apparatus is moved toward the forming machine 21 and the square flange 30 (Figs. 3 and 4) is brought to bear against the block 27. The pins 31 pass through the apertures provided in the square flange 30 and the lugs 33 automatically 60 fall into position in the recesses 34 formed in the pins 31 to lock the apparatus in operative position. In so moving the apparatus from an out of the way position toward the forming machine 21, the links 23 and 24 (Figs. 2) become 65 extended against the action of the coil spring 29.

After the apparatus has been thus moved into its operative position, the height of the central shaft 58 is adjusted by manipulation of the hand wheel 53 (Fig. 2) so that the swabs 64 occupy 70 a position slightly above the level of the cut-off

knives K when the latter are extended. In this manner the swabs 64 will descend upon the knives to properly apply lubricant thereto in the manner previously described when the cam rollers 66 (Fig. 8) ride inwardly upon the flattened area 70 5 of the cam surface 72.

Operation of the lever 13 (Figs. 8 and 11) causes the detent 39 to become disengaged and the clutch bar 79 to be lowered to permit the upper clutch element or collar to descend upon the lower clutch element 85, thus setting the various gears contained within the chamber 82 into motion. The proper gears 128-131, 129-132, or 130-133, are selected for engagement to effect the desired speed ratio between 15 the central shaft 58 and the shaft 108 and control the rate of advancement of the reservoir or cylinder 99 onto the piston. Attainment of the desired speed ratio is effected by properly locating the pin 136 in one of the holes 137, 138 or 139 20 and imparting to the triangular plate 127 the proper angular adjustment about the axis of the shaft 108.

Rotary motion of the forming machine gear 97 (Fig. 5) transmits reciprocal motion to the pusher 25 rod 92 through the pin and slot connection 94. The pusher rod 92 periodically extends the rack bar 88 while the coil spring 90 periodically returns the same to its normal position and thus the rack bar 88 is caused to reciprocate. Reciprocation of the rack bar 88 imparts turning movement alternately in opposite directions to the gear 87 (Fig. 8) formed on the collar 86. During rotary movement of the gear 87 in one direction, the two elements 85, 86 of the ratchet 35 clutch slip upon each other, but during rotary movement of the gear 87 in the other direction the element 85 is caused to rotate, thus turning the shaft 58 and causing the swab-carrying arms 62 and swabs 64 to be moved or turned through 40 an angle of one hundred and eighty degrees. The swabs thus pass over the cut-off knives successively and, as the rollers 66 ride onto the flattened area 70 (Fig. 12) the swabs are lowered into engagement with the knives K to apply lubricant thereto. The swabs also pass over the lubricant feeder 100 in succession during alternate movements of the shaft 58 and receive lubricant therefrom for application to the cut-off knives K. 45

Simultaneously with the operation of the swab-carrying arms 62 and swabs 64, the lubricant reservoir 99 is periodically advanced upon the piston 106 through the medium of the various gears contained within the chamber 82, as previously described, and lubricant is forced upwardly through the flexible conduit 103 to the lubricant feeder 100 for application to the swabs 64. 50

It is to be noted that when the lubricating apparatus is in its operative position in close proximity to the forming machine, the lever 44, which serves to release the latch mechanism 44, 34, which holds the supporting arm 32 in engagement with the attachment block 27 against the action of the coil spring 29, extends upwardly alongside 65 the machine just outside the periphery thereof and is operable to release the latch mechanisms 44, 34, upon movement thereof in the direction of the molds and other moving parts of the forming machine. Thus, if struck by any moving part 70 of the forming machine or by an object or person on the forming machine, the lever would release the latch mechanisms 44, 34, and permit the entire lubricating apparatus to be automatically moved bodily under the influence of the coil spring 29 to 75

an out of the way position as indicated by the dotted lines of Fig. 5.

Modifications may be resorted to within the spirit of the appended claims.

5 I claim:

1. The combination with a rotary glassware forming machine having an annular series of blank molds, a cut-off knife for each mold and means for actuating the knife to sever glass in the mold from a supply body, of a lubricant carrying swab adapted to register and contact with said knives for applying lubricant thereto, and means for moving said swab into contact with successive knives when the latter are out of glass 10 severing position.

2. The combination with a rotary glassware forming machine having an annular series of blank molds, a cut-off knife for each mold and means for actuating the knife to sever glass in the mold from a supply body, of a plurality of lubricant carrying swabs designed for engagement with said knives for applying lubricant thereto, and means for moving said molds, cut-off knives and swabs in unison so that the swabs 20 register and contact in succession with successive cut-off knives when the latter are out of glass severing position.

3. A lubricating apparatus for applying lubricant to the cut-off knives of a rotary glassware forming machine comprising a stationary lubricant feeder, a lubricant transferring device adapted to transfer lubricant from said feeder to successive cut-off knives of said forming machine, and means synchronized with the rotation of said 30 forming machine for periodically actuating said lubricant transferring device.

4. A lubricating apparatus for applying lubricant to the cut-off knives of a rotary glassware forming machine comprising a stationary lubricant feeder, means synchronized with the rotation of said forming machine for periodically supplying predetermined quantities of a lubricant to said feeder, a lubricant transferring device operable upon rotation of the machine, adapted to transfer lubricant from said feeder to the knives one at a time, and means synchronized with the movement of said forming machine for periodically actuating said lubricant transferring device.

5. The combination with a rotary glassware forming machine having an annular series of blank molds, a cut-off knife for each mold and means for actuating the knife to sever glass in the mold from a supply body, of a plurality of movable lubricant carrying swabs designed for engagement with said knives for applying lubricant thereto, a lubricant feeder positioned in the path of movement of said swabs and adapted to be contacted by said swabs upon movement of the latter, and means for moving said molds, cut-off knives 50 and swabs in timed relation so that the swabs successively contact said feeder and register and contact in succession with successive cut-off knives when the latter are out of glass severing position.

6. The combination with a rotary glassware forming machine having an annular series of blank molds, a cut-off knife for each mold and means for actuating the knife to sever glass in the mold from a supply body, of a plurality of lubricant carrying swabs designed for engagement with said knives for applying lubricant thereto, and means synchronized with the rotary movement of said forming machine for periodically moving said swabs in succession into contact 70 with successive cut-off knives when the latter are out of glass severing position.

tact with successive cut-off knives when the latter are out of glass severing position.

7. The combination with a rotary glassware forming machine having an annular series of blank molds, a cut-off knife for each mold and means for actuating the knife to sever glass in the mold from a supply body, of a plurality of radially extending arms mounted for rotation about an axis parallel to the axis of rotation of said forming machine, a swab carried by each arm and adapted upon rotation of said arms to contact and register with successive knives of the forming machine when the latter are out of glass severing position, and means operable upon rotation of said forming machine 10 for rotating said arms.

8. The combination with a rotary glassware forming machine having an annular series of blank molds, a cut-off knife for each mold and means for actuating the knife to sever glass in the mold from a supply body, of a plurality of radially extending arms mounted for rotation about an axis parallel to the axis of rotation of said forming machine, a swab carried by each arm and adapted upon rotation of said arms to 20 contact and register with successive knives of the forming machine when the latter are out of glass severing position, and means operable upon rotation of said forming machine for rotating said arms in a direction opposite to the direction 30 of rotation of said forming machine.

9. The combination with a rotary glassware forming machine having an annular series of blank molds, a cut-off knife for each mold and means for actuating the knife to sever glass in the mold from a supply body, of a plurality of radially extending arms mounted for rotation about an axis parallel to the axis of rotation of said forming machine, a swab carried by each arm and adapted upon rotation of said arms to 35 contact and register with successive knives of the forming machine when the latter are out of glass severing position, a lubricant feeder positioned in the path of movement of said swabs and adapted to be contacted by said swabs upon 40 rotation of said arms, and means operable upon rotation of said forming machine for rotating 45 said arms.

10. A lubricating apparatus for the cut-off knives of a rotary glassware forming machine comprising a stationary lubricant feeder, means operable upon rotation of said forming machine for periodically feeding a predetermined quantity of lubricant to said feeder, and means for transferring lubricant from said feeder individually to successive cut-off knives of said forming machine.

11. A lubricating apparatus for the cut-off knives of a rotary glassware forming machine comprising a stationary lubricant feeder, means operable upon rotation of said forming machine for periodically feeding a predetermined quantity of lubricant to said feeder, means for transferring lubricant from said feeder individually to successive cut-off knives of said forming machine, and means for varying the amount of lubricant periodically fed to said feeder.

12. The combination with a rotary glassware forming machine having an annular series of blank molds and a cut-off knife for each blank 70 mold, of a stationary lubricant feeder, a lubricant transferring device movable repeatedly into contact with said feeder to receive lubricant therefrom and movable thereafter into contact with successive cut-off knives of said forming 75 machine.

machine, and means synchronized with the rotary movement of said forming machine for moving said lubricant transferring device.

13. The combination with a rotary glassware forming machine having an annular series of blank molds, a cut-off knife for each mold and means for actuating the knife to sever glass in the mold from a supply body, of a plurality of radially extending arms mounted for rotation about an axis parallel to the axis of rotation of said forming machine, a swab carried by each arm and adapted upon rotation of said arms to contact and register with successive knives of the forming machine when the latter are out of glass severing position, means operable upon rotation of said forming machine for rotating said arms, and means for adjusting the height of said arms.

14. The combination with a rotary glassware forming machine having an annular series of blank molds and a cut-off knife for each mold, of a lubricating apparatus for applying lubricant to said cut-off knives comprising a vertical shaft mounted for rotation about an axis parallel to the axis of said forming machine, means synchronized with the movement of said forming machine for periodically indexing said shaft to turn the same through an angle of one hundred and eighty degrees, a pair of oppositely extending radially disposed arms mounted on said shaft, a lubricant applying device mounted on the outer end of each arm, a stationary lubricant feeder mounted in the path of movement of said devices and adapted upon successive indexing operations of said shaft to be engaged by said devices alternately to feed lubricant thereto, said devices being adapted upon successive indexing operations of said shaft to alternately contact successive cut-off knives on said machine to apply lubricant thereto, and means synchronized with the movement of said forming machine for periodically feeding predetermined quantities of lubricant to said feeder.

15. The combination with a rotary glassware forming machine having an annular series of blank molds and a cut-off knife for each mold, of a lubricating device for applying lubricant to said cut-off knives comprising a vertical shaft mounted for rotation about a vertical axis parallel to the axis of said forming machine, means

synchronized with the movement of said forming machine for periodically indexing said shaft to turn the same through an angle of one hundred and eighty degrees, a pair of oppositely extending radially disposed arms mounted on said shaft, a lubricant applying device mounted on the outer end of each arm, a stationary lubricant feeder mounted in the path of movement of said devices and adapted upon successive indexing operations of said shaft to alternately be engaged by said devices to feed lubricant thereto, said devices being adapted upon successive indexing operations of said shaft to alternately contact successive cut-off knives on said machine to apply lubricant thereto, and means operable upon each indexing operation of said shaft for feeding a measured quantity of lubricant to said feeder.

16. The combination with a rotary glassware forming machine having an annular series of blank molds and a cut-off knife for each mold, of a lubricating device for applying lubricant to said cut-off knives comprising a shaft mounted for rotation about a vertical axis, means synchronized with the movement of said forming machine for periodically indexing said shaft to turn the same throughout an angle of one hundred and eighty degrees, a pair of oppositely extending radially disposed arms mounted on said shaft, a lubricant applying device carried by each arm, said devices being adapted upon successive indexing operations of said shaft to alternately engage successive cut-off knives on said machine to apply lubricant thereto, and means operable upon indexing of said shaft to apply lubricant to said devices.

17. The combination with a rotary glassware forming machine having an annular series of blank molds and a cut-off knife for each mold, of a stationary lubricant feeder, a lubricant transferring device adapted to engage said feeder to receive lubricant therefrom and to transfer said lubricant to successive cut-off knives on said machine, means for actuating said device in timed relation to the movement of said machine, and means operable upon actuation of said device for feeding measured quantities of lubricant to said feeder.
